STAND FOR SUPPORTING A WASTE CAN OR THE LIKE

Mabel V. Covington, 1506 Franklin Ave.,
Nashville, Tenn.

Filed Nov. 14, 1960, Ser. No. 62,812

Term of patent 3½ years

(Cl. D58—26)

FIG. 1 is a side elevational view of a stand for supporting a waste can or the like, showing my new design, the broken-line representation of a waste can being shown for illustrative purposes only;

FIG. 2 is a top plan view thereof; and

FIG. 3 is a section taken along the line 3—3 of FIG. 2.
I claim:

The ornamental design for a stand for supporting a waste can or the like, as shown and described.
